(54) **CHLORINE, COSMETIC**

(76) Inventor: **David West**

David West, Columbia Co., N.Y.

Litter Patent

The Schedule referred to in this Litter Patent and making part of the same containing a description in the words of the said David West himself of his invention, being a composition of matter denominated Chlorine Cosmetic.

To all to whom these presents shall come:

Know ye that I David West of the City of Hudson in the County of Columbia and State of New York have invented a new and useful composition of matter and that the following is a full and exact description of the mode of compounding and the object and operation thereof as invented by me.

The composition of matter is made by chemically combining animal or infusing Chlorine-gas with and into oils, animal, guineo, mineral, etc., or either of them and which is done, first, by mixing and grinding or rubbing together, the Chloride of Lime or Chloride of Soda with the said Oils, giving guineo animal fat or either of them so as to form a soft untempered, cosmetic or cosmetic or, secondly, it may be done by charging the oil or animal fat with Chlorine-gas by means of a retort or, thirdly, it may be done by charging or infusing into water Chlorine-gas by means of a retort and mixing the water so charged or infused with oily animal fat or either of them and rubbing and stirring them together and then suffusing the water to settle leaving the Chlorine-gas in the oily or animal fat. The oil made of making the composition is by mixing four ounces of Olive oil with four ounces of Chloride of Lime. The object of the composition of matter is to heal & cure ulcers, sores, simple fevers, ring worms, itch, salt, scurvy & scabulous, etc., cases of every description either on man or beast. The composition possesses many powerful antiseptic qualities.

In order to secure to the composition its full medicinal virtues I deem the following the best mode of preparing it. Take four ounces of Chloride of Lime & four ounces of Chloro-alkali add to the oil before mixing it with the Chloride of Lime, four ounces of the airtight of the nitrate of quicksilver in order to give the composition an additional curative quality. Then

add one ounce of the oil of turpentine or of any other essential oil to give the composition a soft consistency then add a half an ounce of the essence of Borage or any other aromatic essential oil to give the composition a perfume. Then grind or rub all these articles together until the composition is of a soft and uniform consistency —

The proportion or quality of the particular articles may be altered or varied care being taken to prevent the chlorine gas, that being the essential ingredient in the composition
